MEANS FOR ADJUSTING THE TENSIONING OF MATERIAL WOUND ON A BEAM

Hermann Fazis, Weil (Rhine), Germany, assignor to David Rothschild, Zurich, Switzerland

Application November 8, 1955, Serial No. 545,707

3 Claims. (Cl. 64—30)

The present invention relates to means for adjusting the tension of material wound on a beam.

The uniform winding and unwinding of strip-shaped material and more particularly of textile material onto and off take up and feed beams leads to difficulties inasmuch as it is possible to obtain a reeled structure of uniform size on a beam only when the tensioning of the material is at least approximately constant throughout the winding or unwinding procedure. Now, since the diameter of the wound material varies constantly during such a winding and unwinding procedure, the driving or braking torque exerted on the beam cannot remain constant and it must vary in accordance with the diameter of the wound material at every moment. To this end, adjusting means have already been proposed wherein a feeler is adapted to test the amount of material wound on the shaft while the value thus measured serves for adjusting correspondingly the torque referred to. Such adjusting means are however comparatively intricate and uneconomical.

It is, therefore, one object of the present invention to provide a quite different method which relies on the fact that it is possible to make the torque exerted on the beam responsive to the weight at the moment considered of the reeled or wound material since the increase and decrease of the reel diameter corresponds to a simultaneous increase and decrease of the reeled weight.

It is another object of the present invention to provide means for adjusting the tension of material wound on a beam, wherein the coupling through which the beam is connected with the arrangement adjusting the tensioning of the material is improved.

It is, thus, still another object of the present invention to provide means for adjusting of material wound on a beam, wherein the introduction of the beam rod into the head of a driving shaft is performed in a much easier and reliable manner.

It is yet another object of the present invention to provide means for adjusting of material wound on a beam, wherein the cooperating parts of the locking member and the projection and recesses are designed in such manner that the handwheel or the like locking member is rocked from its open inoperative position into its operative position automatically through the rotation of the driving shaft, whenever the attendants have neglected to lock the end of the beam rod in the recess in the head of the driving shaft.

With these and other objects in view which will become apparent in the following detailed description, the present invention will be clearly understood in connection with the accompanying drawings, in which:

Figure 1 is a vertical axial section of the coupling in its open inoperative position;

Fig. 2 is a section along the lines 2—2 of Fig. 1, shown on a larger scale;

Fig. 3 is a fragmentary side view of the coupling in its locked or operative position;

Fig. 4 is an end view of the coupling, from the beam rod side.

2

Referring now to the drawing and in particular to Fig. 1, the central bore of an otherwise entirely closed casing 1 carries a rocking ball bearing 2 the inner race of which is rigid with a stub shaft 3. The stub shaft 3 forms a two-arm rocking lever, the rocking axis of which extends through the center 7 of the rocking ball bearing 2. The stub shaft 3 includes a short lever arm 3a projecting out of the casing 1 and the outer end of which carries a supporting member 4 while the other, longer lever arm 3b is completely enclosed inside the casing 1.

The supporting member 4 has a U-shaped vertical cross-section so that it defines a four-sided recess 4a (Fig. 4) open at one end, said supporting member 4 being provided with a shiftable locking member adapted to hold 15 in position one end of the beam 5 and matching the shape of the supporting member engaged thereby. The locking member is constituted in the case shown in the drawing by a handwheel 28, the body of said handwheel being rockably mounted on the supporting member 4 so as to rock 20 upon the transverse axis 29 with reference to the supporting member 4; with a view to introduce and to remove, respectively, the beam 5 into and out of position, the handwheel 28 is shifted into oblique position, shown in Fig. 1, in which position it engages an abutment on the 25 casing formed by a bevelled surface area 1a, while it uncovers the opening in the supporting member 4. Before starting the operation, the handwheel is rocked back into the position shown in Fig. 3 upon its axis 29 until it abuts against a stop 30 on the supporting member 4, 30 at which moment it lies in its locking position perpendicular to the axis of the stub-shaft 3, while the handwheel 28 closes the opening in the supporting member 4 and the beam 5 is locked in a position in which it is coaxial with the axis of the stub-shaft 3.

35 The stationary section 1b at the front end of the casing 1 prevents the return of the handwheel 28 into a position other than that illustrated as long as the four-sided recess 4a in the supporting member 4 is not directed upwardly. In case the driving shaft is caused to turn 40 while the handwheel 28 is in its inoperative position as a consequence of negligence or oversight, the stationary section urges automatically the wheel 28 upwardly and locks thereby of necessity the supporting member 4 in position.

45 The other end of the beam (not shown) can be rotatably mounted in any desired conventional manner. A rotation of the handwheel 28 causes a rotation of the stub-shaft 3 into the position shown in Fig. 1, in which the opening in the supporting member 4 faces upwardly, 50 so as to allow the introduction and removal of the beam 5 into said opening, which operation is furthered through the guiding ribs or fins 28b formed on the web 28a of the handwheel 28.

The longer arm of the lever formed by the stub-shaft 3, which is farther from the supporting member 4 extends through its outer reduced diameter end inside a hollow carrier 9 disposed inside the casing 1 and the upper surface of which is formed as a cam 10 which is engaged by a member constituted by a follower roller 11. To 60 this end, the upper section of the hollow carrier 9 is formed as said cam surface 10 which forms advantageously a spherical cap over which the follower roller 11 is adapted to run. This follower roller 11 is carried by an adjusting lever 12 the inner end of which is rigidly connected with a forked member 31, as illustrated in Fig. 2, as provided by a connection by means of a pin 32. The forked member 31 is provided with a central slot in which the roller 11 is rotatably mounted by means of a transverse spindle 33. The arms 34 of the forked member 31, 70 one of which is shown only in the drawing, form vertical guides for the hollow carrier 9 and are pivotally secured to coaxial pivots 35 one of which only is shown in the

drawing. These pivots 35 are formed by the shanks of screws, engaging corresponding tapped openings formed in the casing 1, the position of said screws being chosen in such manner that the transverse axis 13 formed by the pivots 35 crosses the axis 6 of the stub-shaft 3 (Fig. 1).

As illustrated in Fig. 2, the adjusting lever 12 is tubular and is provided with two diametrically opposed longitudinal slots 36 engaged by a locking pin 15. Said pin is rigidly secured in a corresponding transverse bore of the head 37 of a push rod 38 sliding inside the tubular lever 12 and the outer end of which forms a threaded projection onto which a ball shaped member 26a is screwed.

This ball shaped member 26a is located outside the tubular lever 12 in which a compression spring 39 surrounding the push rod 38 is located, the spring 39 engaging at one end the head 37 of the rod 38 and at its other end the inturned terminal edge of the tubular lever 12. The spring 39 is subjected to a preliminary tensioning so that it constrains the locking pin 15 to remain in its lever-locking position shown in Fig. 2. In this position, the locking pin 15 engages selectively one of the notches 14 in the casing 1 so as to prevent any undesired angular movement of the adjusting lever 12; a series of such notches 14 is formed on the outer surface of the casing 1 to either side of a notch formed symmetrically in the vertical medial longitudinal plane of said casing, and through which slot the adjusting lever 12 projects. These notches thus permit of positioning of the adjusting lever 12 and consequently the follower roller 11 or presser member is retained in any of a number of different angular positions.

The lower surface of the hollow carrier 9, is subjected to the action of a compression spring 40 the lower end of which engages the bottom of the casing 1; the spring 40 urges the surface 10 of the hollow carrier 9 permanently into operative engagement with the follower roller 11 and is guided by a guiding rod 41 extending through it and held between the hollow carrier 9 and the longitudinal slot 42 in the bottom of the casing 1. In the chamber formed inside the hollow carrier 9, the stub-shaft 3 is held by means of two roller bearings 8 and 8a and of a thrust bearing 19 fitted between the latter. This chamber in the hollow carrier 9 encloses also to the rear of the stub-shaft 3 a cup-shaped thrust member 17 which bears against a threaded pivot 16 screwed rearwardly into the centrally tapped bore of the support 9, while it is held fast by a counter nut in the adjusted position assumed by it. Said thrust member 17 engages the outer race of the ball bearing 8a which engages on the other hand a spacing member 18 fitted between said roller bearing 8a and the thrust bearing 19. On the opposite side of said thrust bearing 19, is inserted a ring 20 cooperating with the inner race of the farther ball bearing 8, which latter engages the cap-shaped transmission member 21 projecting partly out of the hollow carrier 9. This transmission member 21 cooperates in its turn with an annular plate 22 which is held against rotation by means of the medial section of the stub-shaft 3, by the grippers 23 while remaining axially shiftable. At a short distance from said plate 22 is mounted on the same section of the stub-shaft 3 a second similar plate 22a held also against rotation by grippers 23a, the two plates 22 and 22a forming together with an abutment plate 43 rigid with the stub-shaft 3, one half of a friction coupling, the other half of which is formed by a chain wheel 26 and an auxiliary wheel 25 sliding longitudinally with reference to the wheel 26 and revolving in unison therewith by means of transverse pins 27. The auxiliary wheel 25 is freely rotatable between the brake linings 24 and 24a which latter are carried by the sides of the clutch plates 22 and 22a which face each other. The chain wheel 26 is freely rotatable with reference to the stub-shaft 3 by interposition of a ball bearing 44 and it is permanently turned in a manner (not shown) by means of a motor-driven chain, the rota-

tion of which is performed in the desired direction of rotation of the beam 5.

The fraction of the weight transferred by the beam 5 through its rod to the supporting member 4, which corresponds normally to one half of the weight of the loaded beam 5 at the moment considered, is transferred again, proportionally with the ratio between the operative lever arms of the stub-shaft 3 to either side of their pivotal axis 7 and through the bearings 8, 8a and 19, onto the carrier 9 and from the latter to the roller or the like presser member 11. The reaction pressure thus produced is shown in Fig. 1 by the arrow P and may be divided into a vertical component V and a horizontal component H. The vertical component V balances the fraction of the weight of the beam 5 which acts on the supporting member 4 whereas the horizontal component H is transferred through the screw 16 to the thrust member 17 and thence through the outer race of the ball bearing 8a, the spacing member 18, the thrust bearing 19 and the ring 20 to the inner race of the bearing 8 and thence through the transmission member 21 to the plate 22. This leads to a corresponding slight axial shifting of said plate 22, accompanied by a corresponding shifting of the plate 22a whereby the friction coupling is engaged to an extent depending on the magnitude of the compression force H and consequently the coupling linings 24 and the like transfer a corresponding torque to the plates 22 and 22a and therethrough to the stub-shaft 3 so that the beam 5 is angularly rotated through the supporting member 4.

Thus, as the winding procedure progresses and the weight of the beam increases, the horizontal component H defining the force exerting on the friction coupling increases correspondingly, which horizontal component is produced by the reaction of the follower roller 11. Consequently the driving torque transferred through the friction coupling increases in such manner that at least approximate constancy of tensioning for the material that is being wound is achieved, regardless of the gradual modification in the diameter of the reel on the beam 5.

Instead of exerting a driving torque, it is possible also to exert a braking torque on the beam 5 so that the chain wheel 26 is no longer driven, but is braked.

In so far as the speed of rotation of the chain wheel is higher than the speed of rotation of the beam 5 as should always be the case, when driving the beam 5 through the friction coupling, the latter obviously slips.

When one wishes to shift the control lever 12, the attendant takes hold of the ball 26a and draws out the latter, by compressing the spring 29 to release the locking pin 15 with reference to the notch 14. One may thus rock the lever 12 into another position and after release of the ball 26a by the attendant, the spring 39 urges the pin 15 inwardly so as to engage another notch 14 facing it. As it is apparent from Fig. 1, the lever 12 can be rocked beyond its vertical position whereby the positioning force H reaches a zero value, so that the coupling is disengaged.

While I have disclosed one embodiment of the present invention, it is to be understood that this embodiment is given by example only and not in a limiting sense, the scope of the present invention being determined by the objects and the claims.

I claim:

1. A weight sensitive friction coupling comprising a casing having a centrally disposed bore, a pivot-type bearing having an inner and an outer race disposed in and carried by said casing, a shaft rigid with said inner race and mounted in said casing for rotating movement and for rocking movement upon a pivot point disposed in the rotating axis of said shaft, one end of the latter being adapted to be subjected to a variable weight, a swingable lever pivotally secured to said casing and adjustable to a plurality of angular positions relative to the rotating axis of said shaft, and means for exerting a thrust in axial direction of said shaft from said lever

dependent upon its angular position, a friction coupling including two sections, one of said sections constituting driving and braking means, respectively, and the other of said sections being secured to said shaft for common rotation, said one end of said shaft permitted to perform a rocking movement to vary the friction of said coupling as a function of the weight placed upon or removed from said shaft, and, thereby to vary the speed of rotation of said shaft.

2. The coupling, as set forth in claim 1, wherein said shaft constitutes a double lever rockable in said pivot-type bearing.

3. The coupling, as set forth in claim 2, wherein said

other end of said shaft is mounted in a thrust-bearing, and a hollow carrier receiving said thrust-bearing, said carrier having an outer cam face and a follower roller rotatably mounted in said lever and engaging said cam face in the plurality of positions of said lever.
